UNITED STATES PATENT OFFICE.

FRANCIS SERVICE, OF EBBW VALE, COUNTY OF MONMOUTH, ENGLAND.

CRANE.

SPECIFICATION forming part of Letters Patent No. 363,424, dated May 24, 1887.

Application filed April 27, 1886. Serial No. 200,376. (No model.) Patented in England February 7, 1884, No. 2,882.

To all whom it may concern:

Be it known that I, FRANCIS SERVICE, a subject of the Queen of Great Britain, and a resident of Ebbw Vale, in the county of Monmouth, 5 and in the country of England, have invented certain new and useful Improvements in Cranes and Apparatus for Hoisting, Loading, and Unloading Materials, &c., into and out of Vessels; and I do hereby declare that the following is a full, clear, and exact description thereof.

The object of my invention is to produce a new and useful hoisting apparatus which can be used for loading and unloading vessels, barges, &c.

Referring to the drawings, Figure 1 is a front view of my improved hoisting apparatus. Fig. 2 is a sectional elevation of the same on line *x x*, Fig. 1. Fig. 3 is a plan view 20 of the same. Fig. 4 is an enlarged side view of one of the boxes. Fig. 5 is an end view of Fig. 4. Fig. 6 is a sectional elevation of Fig. 4.

A is a post, of any required length, fastened 25 to a base, *B*. To this post, at the top, is attached the sliding bracket *C*, having bearings *c c'* for the pivot-pins *d d'* of the swinging arms *D D'*. *E* is a rod having bearing in horizontal bracket *c*, fastened to the top of the sliding bracket *C*, and in the horizontal brackets or bearing *b* in the base *B*. This rod is turned 30 by operating lever *F*. This rod is also connected to the swinging arms *D D'* by toggle-levers *f f' f' f''*. Now, by moving the operating-lever *F* to the right or left, the swinging arms *D D'* are swung in any direction. The sliding bracket-frame *C* is so adjusted upon 35 the post as to permit its sliding up and down the same for the purpose of raising and lowering the swinging arms *D D'*. In order to do this, the horizontal bracket *c* is so arranged as to permit the rod *E* to slide through the same. Likewise the toggle-levers *f f'* are so fastened to the shaft as to permit said rod to slide up and down on the same. To permit 40 this, and also to permit the rod to turn the swinging arms *D D'*, the said rod is made square. The sliding bracket *C* is raised or lowered by ropes *g g*, which are fastened to bracket at *c*, passing over sheaves at *d d'* down to drum *H*, supported on brackets on the base *B*.

I is the hoisting-cable or chain, fastened at

one end to boxes *J*, passing over sheaves *k k*, attached to swinging arms *D D'*, thence down 55 under sheaves *b b'* of the base, around arm *H*, over sheaves *L* on the sliding bracket *C* to the weights *M M*, where they are attached. This chain *I* is operated by steam-engine power, as shown in Fig. 2, or by manual 60 power. As the boxes are lowered the weight is raised, thus counterbalancing the load.

The boxes *J J* are constructed with hinged sides *j j*. These sides are held up in place, as shown in Fig. 5, by four pivoted lever-catches, 65 *o o*, which are pivoted to the sides of the box and connected to the supporting-bars or sliding arms *n n*, which are held to the box by bolts or pins *n' n'*, passing through slots *n* in said arms. These arms are further held to the 70 box by guide-plates *n' n'*. The upper ends of these arms are bent, as shown in Fig. 4, and join each other at point *n*, where they are pierced with a hole, through which passes the cable-hook. (See Fig. 4.) Now, when the 75 loaded boxes are required to be emptied they are lowered upon the proper place, and as soon as they come to rest upon the ground the sliding arms *n n* drop down the length of the slots *n*, which immediately raises the pivoted 80 lever-catches *o o* and releases their hold upon the hinged sides *j j*, and allows them to fall down, as shown in Fig. 6. By this arrangement the boxes can be automatically opened 85 by their own weight without the use of additional ropes or cables.

Having thus described my invention, I desire to claim—

1. The combination of the sliding bracket *C* and its hoisting-cables with the swinging arms *D D'*, the toggle-levers *f f' f' f''*, and the operating-levers *F*, provided with a suitable handle, all substantially as and for the purpose set forth.

2. The combination of the sliding arms *n n*, 95 adapted to support the box *J*, with the pivoted lever-catches *o o* and the hinged sides *j j*, all substantially as described.

In testimony that I claim the foregoing I have hereunto set my hand this 29th day of 100 December, 1884.

FRANCIS SERVICE.
